UNITED STATES PATENT OFFICE.

THOMAS H. BALE, OF PETERSBURG, ILLINOIS.

MILLSTONE-DRESS.

SPECIFICATION forming part of Letters Patent No. 233,132, dated October 12, 1880.

Application filed May 7, 1880. (No model.)

To all whom it may concern:

Be it known that I, THOMAS H. BALE, of Petersburg, in the county of Menard and State of Illinois, have invented certain new and useful Improvements in Millstone-Dresses; and I do hereby declare the following to be a full, clear, and exact description of the invention, such as will enable others skilled in the art to which it appertains to make and use the same, reference being had to the accompanying drawings, and to letters of reference marked thereon, which form a part of this specification.

It is known that the best mode of producing a superior grade of flour is by first reducing the grain into middlings, and then grinding the middlings (after being purified) into flour; and the main object to be accomplished in milling is to produce the greatest quantity of middlings without "flouring" the grain on the first grinding, and yet to clean the bran sufficiently to render the regrinding of same unnecessary.

The object of my invention is to accomplish these results; and the nature of my peculiar style of dress for millstones will clearly be seen from the following description and claims.

Referring to the drawings, Figure 1 is a plan view of my improved millstone-dress. Fig. 2 is a sectional face of the small portion cut from the millstone by the line $x-x$ of Fig. 3. Fig. 3 is a perspective view of a portion of the millstone-dress; and Fig. 4 is a detail sectional view of a modification of my improved dress.

Corresponding parts in the several figures are denoted by similar letters of reference.

In the annexed drawings, A marks the tangential leading furrows, extending from the eye to the skirt of the stone, and $a-a'$ the second and third furrows, respectively, which branch from the leading furrows, all cut in the usual manner.

The peculiar construction of the grinding-surface divided by the furrows, and which are termed "lands," constitutes the subject-matter of my invention. These lands are each formed of a narrow high portion or plane, b , which is flush or even with a line marking the face of the stone, and a reduced or depressed portion or plane, b' , parallel to but lower than said

high portion b , as clearly shown in Figs. 2 and 3.

The high portion b , it will be seen from the drawings, is next to the back of the furrow, and the reduced or depressed portion b' of the land is between said high portion and the feather-edge of the furrows.

It will be further observed that the lands, composed of the high portion b and reduced or depressed portion b' , like the furrows, are evenly and regularly arranged on the face of the stone, and the lands next to the leading furrows A extend, like said furrows, from the eye to the skirt of the stone.

The upper and lower stone are dressed in the manner described, or the lower stone alone may be so dressed.

In the ordinary dress having wide high lands the stones must be run far apart to prevent flouring, in which event the crushed grain is discharged without cleaning the bran; or to clean the bran the stones must be run near together, which will flour the middlings. With my dress the grain, as it enters the eye of the upper stone, is crushed, and the high parts of lands being arranged close together, the bran passes over said high parts and is cleaned of the rich finer middlings, while the bulk of the middlings is made upon and by the reduced or depressed portion of lands and discharged at the skirt of the stone. The high portion of the lands is alone intended to thoroughly clean the bran. The reduced or depressed portion of the lands is made deeper or shallower, as desired, to make the middlings coarser or finer.

By my mode of dressing the stone or stones enough middlings can be produced from one pair of stones to constantly feed another or flouring-stone, which grinds the middlings into flour. By the old style of dress it requires two or more pairs of stones to supply middlings for one flouring-stone.

Fig. 4 shows a modification of my dress, in which, instead of arranging the high portion of the lands next to the back of the furrows, the reduced or depressed portion is so arranged.

Having thus fully described my invention, what I claim, and desire to secure by Letters Patent, is—

1. A millstone having its grinding-surface

divided by furrows into lands formed of planes of different heights, said planes being in contact and parallel with each other, substantially as and for the purposes set forth.

5 2. A millstone having its grinding-surface divided by furrows into lands formed of the contiguously arranged narrow high plane *b* and the reduced or depressed plane *b'*, said plane *b* lying next to the back of the furrow 10 and plane *b'* between the feather-edge thereof

and plane *b*, substantially as shown, and as and for the purposes set forth.

In testimony that I claim the foregoing I have hereunto set my hand this 20th day of April, 1880.

THOMAS H. BALE.
